UNITED STATES PATENT OFFICE.

WILLIAM LANYON, JR., OF PITTSBURG, KANSAS, ASSIGNOR OF ONE-HALF
TO NED V. LANYON, OF SAME PLACE.

DESIGN FOR A PAPER-WEIGHT.

SPECIFICATION forming part of Design No. 21,497, dated April 26, 1892.

Application filed March 25, 1892. Serial No. 426,436. Term of patent 14 years.

To all whom it may concern:

Be it known that I, WILLIAM LANYON, Jr., of the city of Pittsburg, Crawford county, and State of Kansas, have invented and produced a new and original Design for Paper-Weights, of which the following is a full, clear, and exact description, reference being had to the accompanying drawings, forming a part hereof.

10 In the drawings, Figure 1 is a perspective view of the paper-weight, illustrating my new design; and Fig. 2 is a vertical section of the same.

15 The leading feature of my design is an ornamental base having an irregular body mounted thereon.

Referring to the drawings, 1 represents a rectangular base having ornamental depres-

sions formed in the same upon the upper surface thereof, and 2 a lustrous irregular body 20 mounted upon said rectangular base. The bottom of the base 1 is provided with a depression 3, having inclined sides, which presents a finished appearance to the said base at that portion of the same.

Having now described my new design, what I claim as new, and desire to secure by Letters Patent, is—

25 The design for a paper-weight, substantially as herein described and shown.

30 In testimony whereof I affix my signature in presence of two witnesses.

WILLIAM LANYON, JR.

Witnesses:

JAS. PATMOR,

A. K. LANYON.
